United States Patent Office.

SOLOMON C. SPRING, OF BRISTOL, CONNECTICUT, ASSIGNOR TO
"WELCH, SPRING & CO.," OF SAME PLACE.

Design No. 3,536, dated June 8, 1869.

DESIGN FOR A CLOCK-CASE.

The Schedule referred to in these Letters Patent and making part of the same.

To all whom it may concern:

Be it known that I, SOLOMON C. SPRING, of Bristol, in the county of Hartford, and State of Connecticut, have originated and designed a new Design for a Clock-Case, of which the following is a full, clear, and exact description, reference being had to the accompanying drawing, making part of this specification, which drawing is a front elevation of my invention.

The top of the case is square.

A designates the band on the front of the case.

Inside of the band A is a gilded moulding, B, and inside of the gilding is a narrow band or rib, C.

Inside of the three bands is the sash D, the sides, top, and bottom of which adjoin the wood-colored

band or rib C, the latter extending all around the door, as shown in the drawing.

The bands, with the exception of the gilded band B, are wood-colored.

The whole are combined, as shown, to produce a rich and pleasing design for a clock-case.

What I claim as new, and desire to secure by Letters Patent, is—

The design for a clock-case, herein shown and described.

SOLOMON C. SPRING.
